UNITED STATES PATENT OFFICE

91,893

DESIGN FOR A BURIAL VAULT

Walter J. Michael, Bucyrus, Ohio

Application February 5, 1934, Serial No. 50,612

Term of patent 14 years

To all whom it may concern:

Be it known that I, WALTER J. MICHAEL, a citizen of the United States, and resident of the city of Bucyrus, county of Crawford, State of Ohio, have invented a new, original, and ornamental Design for a Burial Vault, of which the following is a specification, reference being had to the accompanying drawing, forming a part thereof.

In the drawing:

I claim:

The ornamental design for a burial vault as shown.

In testimony whereof I have hereunto signed my name to this specification.

WALTER J. MICHAEL.
